UNITED STATES PATENT OFFICE.

DILLWYN M. BELL, OF CHICAGO, ILLINOIS.

KEY LOCK.

Application filed April 22, 1920. Serial No. 375,869.

To all whom it may concern:

Be it known that I, DILLWYN M. BELL, a citizen of the United States, residing at Chicago, in the county of Cook and State of Illinois, have invented certain new and useful Improvements in Key Locks, of which the following is a specification.

This invention relates to improvements in key-operated locks, and more particularly to that class of key-operated locks which are known as cylinder locks.

One object of the invention is to provide a master key lock of this class wherein a single master key may be common to all possible pass or individual key changes; and to this end the present improvements contemplate the provision of a lock having a plurality of independent sets or series of tumblers, one set being adapted to be operated by the pass or individual key and the other set by the master key, the operation of either set permitting the tumbler-carrying barrel to be rotated, to actuate thereby the bolt or other locking mechanism.

As is well known, with cylinder locks of the various types heretofore designed only a very limited number of changes are possible, which will be common to a single master key. Accordingly, for a large number of locks having different individual keys a number of master keys are required. With the present improvements, however, any number of locks, all requiring different individual keys, may be mastered with one and the same master key, this being accomplished without sacrificing any of the advantages realized in cylinder locks as heretofore constructed.

From the above the practical and economical advantages of the present improvements will be readily suggested to those skilled in the art. Other objects and advantages will appear from the following description; taken in connection with the accompanying drawings wherein one form of the improvements is shown embodied in two different types of cylinder locks.

Figure 1 is a longitudinal sectional view of one form of cylinder lock showing the present improvements embodied therein; and the manner of operating the same by means of the master key;

Fig. 2 is a sectional view, taken on the line 2—2 of Fig. 1;

Fig. 3 is a sectional view, taken on the line 3—3 of Fig. 1;

Fig. 4 is a side elevation of the tumbler carrying barrel of the lock;

Fig. 5 is a side elevation, partly in section, of the cylinder or casing for receiving the barrel of the lock;

Fig. 6 is a longitudinal sectional view, taken through the casing of a lock on a plane at right angles to that of the section shown in Fig. 1, and illustrating the tumbler-carrying barrel in elevation in its proper position for mastering;

Fig. 7 is a longitudinal sectional view of a lock showing the manner in which the same is operated by means of the individual or pass key;

Fig. 8 is a sectional view, taken on the line 8—8 of Fig. 7;

Fig. 9 is a longitudinal sectional view, showing the application of the present improvements to a cylinder lock of different construction and the manner in which the same is operated by its individual or pass key.

Fig. 10 is a sectional view, taken on the line 10—10 of Fig. 9;

Fig. 11 is a longitudinal sectional view, similar to that disclosed in Fig. 9 and showing the manner of operating the same by means of the master key.

Fig. 12 is a sectional view, taken on the line 12—12 of Fig. 11;

Fig. 13 is a longitudinal sectional view of the lock shown in Fig. 11, this section being taken on a plane at right angles to that of Fig. 11; and

Fig. 14 is a sectional view, taken on the line 14—14 of Fig. 13.

Referring more in detail to the drawings, and particularly to Figs. 1—8 inclusive, the lock is shown as comprising the usual casing or cylinder 10, the tumbler-carrying barrel 11 mounted therein, and the bolt or lock mechanism 12. The latter, of course, may be of any desired construction, it being shown in the drawings in the form of a sliding bolt 13, having an elongated slot 14 designed to receive the stud 15, eccentrically mounted on the rear end of the barrel 11, so that upon rotation thereof the bolt will be either advanced or retracted, depending on the direction of rotation, to thus move the bolt into locked or unlocked position.

In the form of the invention shown in Figs. 1 to 8, inclusive, the barrel 11 is shown provided with two independent sets or series of tumblers 16 and 17 slidably mounted

transversely therein. The barrel in the lock shown is formed in two semi-cylindrical sections or segments 18, provided with oppositely projecting fingers 19, which interfit 5 when the segments are clamped together so as to provide two sets or series of slots or apertures 20 extending transversely through the barrel. These apertures or slots receive the tumblers and serve to house and guide 10 the same in their reciprocatory movements. Each segment or section is also formed so that when they are clamped together a central keyway or aperture 21 is provided in the barrel, and the tumblers, 16 and 17, of each 15 set or series are provided with laterally projecting lugs 16^a and 17^a, respectively, designed, when the tumblers are in position, to project into this keyway 21 in such wise that they may be raised or lowered by engagement 20 within grooves formed in the sides of the operating key upon insertion or withdrawal of the latter.

In cylinder locks as now constructed, the tumblers, when of block construction, project when in locked position into diametrically opposite longitudinally extending grooves provided in the inner surface of the cylinder or casing, so that rotation of the barrel relatively to the casing is prevented. 25 In cylinder locks of the pin tumbler type, as now constructed, the tumblers when in locked position engage recesses provided in the inner surface of the casing or cylinder, to prevent rotation of said barrel. The barrels of these prior locks are capable only of 30 a rotary movement upon alinement of the tumblers, and it is a prerequisite to such rotary movement that all of the tumblers be alined. In short, if but one tumbler is in engagement with its slot or recess, the rotation or operation of the barrel is prevented.

As distinguished from this, the present improvements contemplate broadly the provision of two independent sets of tumblers, 45 the operation of either set permitting the tumbler-carrying barrel to be rotated, regardless of the positions of the tumblers in the other set. From this it will be readily appreciated that the lock embodying the 50 present improvements may be provided with an individual or pass key which will aline only one of the sets of tumblers, leaving the other set in its projected position, while this latter set may be constructed and so arranged in any number of locks requiring different individual or pass keys, so that all of 55 said locks may be mastered by one and the same master key.

According to the present improvements 60 the above results are realized by the provision of two diametrically opposite grooves 23 in the inner surface of the casing 10, these grooves extending longitudinally of the casing and being common to all of the tumblers 65 16 of one of the sets, and a series of individ-

ual grooves 24 for the tumblers 17 of the other set, these latter grooves also being formed in the inner surface of the cylinder 10, but extending around the same in planes at right angles to the grooves 23 and intersecting said grooves. It will thus be apparent that when the tumblers 16 and 17 are in their projected positions the barrel 11 is held against longitudinal movement by the engagement of the tumblers 17 within the circular grooves and against rotative movement by engagement of the tumblers 16 within the longitudinal grooves. The inner end of the casing or cylinder is provided with an outstanding collar 25, which is provided with two diametrically opposite slots 26, the bottoms of which terminate in the same plane with the inner end of the barrel 11 when the latter is in its normal position, as shown in Fig. 7.

Interposed between the inner end of the barrel 11 and the adjacent side of the lock mechanism housing 27 is a ring-shaped element 28 provided with diametrically opposite lugs or projections 29, designed for engagement within the slots 26 in the collar 25. These lugs or projections are in the form of pockets or seats designed to receive one end of the coil springs 30, the other end thereof seating against the adjacent wall of the housing. The barrel is, as above indicated rotatably and longitudinally slidably mounted within the casing or cylinder, both of these possible movements, however, being prevented when both sets of tumblers are in engagement with their respective grooves. The tumblers 16 of the set which engages the longitudinal grooves 23 are adapted for operation by the pass or individual key 50, as shown in Figs. 7 and 8; and to this end the operating groove 50^a provided in said key is so designed that upon full insertion thereof the said tumblers 16 will be alined in the barrel, thus permitting said barrel to be rotated. The engagement of the other set of tumblers, which are not operated by the individual key, within the circular grooves permits this rotation of the barrel, notwithstanding their offset relation. The other side of the individual key, that is, the side which upon insertion of the key lies next adjacent the lateral lugs of the tumblers 17 of the master key series, is also grooved for receiving said lugs, but the groove is of no particular shape or design, it being merely provided to permit of the unobstructed passage of the key back and forth within the keyway.

The master key 60 is provided with a groove 60^a designed to operate or aline the tumblers 17 of the said master key series, and is also provided with oppositely projecting studs 31 designed to engage the outer end of the barrel when the tumblers 17 have been alined. With the tumblers 17 with-

drawn from their circular grooves 24 in this manner, it will be observed that by thrusting the key forward the barrel, by reason of the latter being engaged by the studs 31 of the key, will also be moved forward or in a longitudinal direction within the cylinder. This forward longitudinal movement of the barrel within the casing is limited by the shoulders 32 provided on the master key 10 coming into engagement with the adjacent wall of the cylinder or casing. This longitudinal movement of the barrel, as will be observed, moves or slides the projecting tumblers 16 of the pass or individual key series along within their longitudinal grooves 23; and the shoulders 32 of the master key are so positioned that this inward movement is stopped when the tumblers of this pass or individual key series are in alignment with the circular grooves 24. As soon as the projected tumblers are so positioned within the casing the barrel is free to rotate, as will be readily appreciated.

During the inward movement of the barrel in the manner just described, it will be observed that the ring-shaped element 28, which overlies the end of the barrel will also be advanced, and during such movement will cause the coil springs 30 to be compressed. Immediately upon the rotation of the barrel in such wise as to re-position the pass key tumblers within their longitudinal grooves 23, the said springs 30 will automatically return the barrel to its normal position. Obviously, the side of the master key corresponding to the pass key tumblers need not be provided with a groove of any particular or definite design, as it is not required that such a slot do anything but merely receive the lateral lugs of this series. In short, the operation of the lock by means of the individual key is entirely independent of the operation of the same by means of the master key, and vice versa.

As will be readily appreciated by those skilled in the art, with the number of pass or individual key tumblers shown in the drawings, the variation in combinations or pass key changes runs practically into infinity, so that substantially any number of locks may be provided, all requiring a different pass or individual key in order to operate them. Yet, regardless of the number of varying combinations or changes devised, a master key tumbler arrangement may be employed which will be common to all such locks, so that they may all be mastered with the aid of a single master key.

Referring now particularly to Figs. 9 to 14, inclusive, the improvements are here shown as applied to a cylinder lock of the type employing the so-called apertured block tumblers. Here, also, the tumbler-carrying barrel 33 is both rotatably and longitudinally slidably mounted within the

casing or cylinder 34, and said cylinder is provided with two sets of grooves, one set comprising the two longitudinally extending grooves 35 and the other set the circular grooves 36, as described above in connection with the other figures of the drawings. The barrel 33, in the form shown in Figs. 9 to 14, inclusive, is provided with the transverse slot 37, in which are slidably mounted a plurality of block tumblers 38, each apertured, as at 39, to provide a keyway, the apertures in the various tumblers being disposed in different positions longitudinally of the tumblers when their ends are in alignment. The operating key is serrated on both edges, so as to engage and operate the tumblers upon insertion of said key. Each tumbler is provided with oppositely projecting lugs 40, and the tumblers are so arranged within the transverse slot 37 that the lugs on every other tumbler lie on one side of the longitudinal axis of the barrel, while the lugs on the other tumblers lie on the opposite side of said axis. In applying the present improvements to a lock of this character, the tumblers having their lugs on one side of the longitudinal axis are selected as the pass or individual key tumblers, while the remaining ones are selected for operating the lock by means of the master key. The pass or individual key 70 is so designed or serrated that upon insertion thereof it will align the tumblers whose lugs project into the longitudinal grooves 35, so that in this manner the barrel may be rotated and the lock operated. The master key 80 is serrated or designed to operate the other set of tumblers, so that the projecting lugs thereof will be withdrawn from their respective circular grooves 36, thereby permitting the barrel to be moved longitudinally within the casing, as hereinbefore described, so as to align the projecting lugs of the other set of tumblers with said circular grooves, whereupon, as will be readily understood, the barrel may be rotated. In this adaptation of the improvements the barrel is returned to normal position after it has been rotated, so as to re-position the pass key tumblers in their longitudinal grooves by the spring means above described in detail in connection with the other illustrations. The master key in these figures is also provided with diametrically opposite studs 80^a designed for engagement with the outer face of the barrel, in order that said barrel may be moved longitudinally upon the bringing of pressure to bear upon the key after the master key tumblers have been aligned, and the alignment of the pass key tumblers with the circular grooves is governed by the provision of shoulders 80^b on the master key which abut against the adjacent face of the cylinder or casing 34, in the same manner as hereinafter described.

While the present improvements have been shown as applied to only two types of cylinder locks, it is desired to point out that the principle and mode of operation are applicable to practically all cylinder locks heretofore constructed, whether they be of the pin or block tumbler types. It is believed that the present invention is the first to employ in a cylinder lock two distinct sets or series of tumblers, each being entirely independent of the other in operation, whereby an unlimited number of locks having a common master key but each requiring a distinct pass or individual key, may be constructed.

In addition to the features and general application of the present improvements from the master key lock viewpoint, it is desired to point out one of its more specific adaptations. As is well known, it is desirable in apartment buildings to provide a lock for the entrance door to such a building which is common to all the pass or individual keys carried by the tenants. In short, the pass key for any of the entrance doors to the various apartments is made to operate the lock in the entrance door to the building. Heretofore, in order to accomplish this result, the lock of the entrance door was provided with only one and in some instances two tumblers, so that by merely providing the pass keys to the apartments with a corresponding number of extra serrations each of these keys could be used in opening the lock in the entrance door to the building, the other serrations on these keys enabling the holder to lock or unlock the door to his apartment. With such a very few tumblers in the lock of the entrance door to the building, it is an easy matter to pick such lock, and it will be found in present-day practice that substantially all locks in entrance doors to apartment buildings are insecure in this respect because of this practice. With the present improvements an entrance door to an apartment building may be provided with a cylinder lock just as secure and safe, and as difficult to pick as any of the other locks in the building, while at the same time such entrance door lock may be made common to all of the keys in the possession of the various tenants. When the present improvements are applied in such connection, one of the two independent sets of tumblers would be employed as pass or individual key tumblers for the locks in the various entrance doors to the apartments, while the other set of tumblers would be employed in these locks as the master series. In the lock for the entrance door of the building, however, this arrangement would be just the reverse, viz., the set of tumblers in this lock corresponding to the pass or individual key tumblers in the other

locks would be the master key series, while the set corresponding to the master key series in the other locks would be the pass or individual key series.

The above applies more particularly to locks of the type shown in Figs. 1-8, inclusive, where the tumblers are operated by means of grooves in the sides of the key, for in locks having keys of this type the groove in one side thereof would be made to operate the apartment door locks, and the groove in the other side the building entrance door lock. Thus each key would serve for two entirely different yet equally secure locks.

It will be obvious to those skilled in the art that the invention is susceptible of various changes and modifications; and in view thereof it is not desired to limit the same to the particular embodiments or adaptations herein shown and described, except where limitations appear in the appended claims.

I claim:—

1. In a master key cylinder lock, a casing, a barrel rotatably mounted therein, a plurality of tumblers carried by said barrel and normally engaging said casing, a portion of said tumblers being operable by means of a master key, and another portion thereof being operable by means of an individual or pass key, the operation of either of said portions permitting rotation of said barrel within said casing.
2. In a cylinder lock, a casing, a barrel rotatably and slidably mounted therein, two sets of slidable tumblers mounted transversely in said barrel, the ends thereof normally protruding beyond the perimeter of said barrel and engaging grooves in said casing to prevent movement of said barrel relatively thereto, and means whereby said barrel may be rotated upon the withdrawal of the tumblers of either set from said grooves.
3. In a cylinder lock, a barrel, a casing therefor, a plurality of tumblers carried by said barrel and adapted to engage said casing to prevent movement of said barrel relatively thereto, and means whereby said barrel may be rotated upon disengagement of only a portion of said tumblers from said casing.
4. In a cylinder lock, a casing, a barrel rotatably and slidably mounted therein, a plurality of tumblers carried by the barrel and normally engaging grooves in the casing, certain of said grooves extending longitudinally of the casing and the others extending around said casing and intersecting said first-named grooves.
5. The combination in a cylinder lock having the usual rotatable barrel, of an inclosing casing therefor provided with a longitudinal groove and a plurality of circular

- grooves, and a plurality of independently operable sets of tumblers carried by said barrel, one set engaging the longitudinal groove of said casing and the other set engaging the circular grooves thereof, said circular grooves intersecting said longitudinal groove. 5
6. In a cylinder lock, a casing provided with a longitudinal groove and a plurality of circular grooves, a barrel rotatably and slidably mounted in said casing, and a plurality of independently operable sets of tumblers slidably mounted transversely in said barrel, one set being designed to engage the longitudinal groove of said casing and each tumbler of the other set being designed to engage one of the circular grooves thereof, the latter intersecting said longitudinal groove, whereby said barrel may be rotated 10 upon withdrawal of said first-named set of tumblers from said longitudinal groove irrespective of the position of said second named set or by withdrawing said second named set from said circular grooves and sliding said barrel longitudinally within said casing until said first named set is alined with said circular grooves. 15
7. In a cylinder lock, a barrel provided with a plurality of slidable tumblers transversely mounted therein, said tumblers normally protruding beyond the perimeter of said barrel, and a casing for said barrel provided with two sets of grooves, each set intersecting the other and designed to receive 20 the protruding ends of said tumblers. 35
8. In a cylinder lock, a barrel, a casing therefor, two sets of tumblers carried by said barrel and engaging grooves in said casing, and means whereby the disengagement of either of said sets from said grooves permits of said barrel being rotated within said casing. 40
9. In a cylinder lock, the combination with the barrel and casing thereof, of two independent sets of tumblers carried by said barrel and normally engaging said casing, the alinement of either set within said barrel permitting the latter to be rotated irrespective of the positions of the tumblers of 45 the other set. 50
10. In a cylinder lock, a casing, a barrel rotatably mounted therein, a plurality of sets of tumblers slidably mounted in said barrel transversely thereof, said tumblers being of a length substantially equal to the diameter of said barrel, the ends of said tumblers normally projecting beyond the perimeter of said barrel, said casing being provided interiorly with a plurality of 55 grooves for receiving said projecting ends, one of said grooves extending longitudinally of said casing and being common to all the tumblers in one of said sets, the others of 60 said grooves extending around the inner surface of said casing in planes substantially 65
- at right angles to said longitudinal groove, there being one of these latter grooves for each of the tumblers in the other of said sets, an individual or pass key for said lock designed to aline the ends of the tumblers of the set which engage the longitudinal groove, whereby the barrel may be rotated without withdrawing the tumblers of the other set from their grooves, a master key 70 designed to aline the other set of tumblers, and means whereby after this latter alinement said barrel may be moved longitudinally within said casing to position each tumbler of the other set in alinement with one of said annular grooves, whereby the barrel may be rotated by means of said master-key without withdrawing the pass key tumblers from said longitudinal groove. 75
11. In a cylinder lock, a casing, a barrel therein, a series of master key tumblers and a series of pass key tumblers slidably mounted transversely in said barrel and designed to engage respectively circular and longitudinal grooves in said casing, the circular grooves lying in planes extending at 80 right angles to the longitudinal grooves and intersecting the latter at points intermediate the pass key tumblers, whereby said barrel may be rotated by either a withdrawal of 85 said pass key tumblers from said longitudinal grooves or by the withdrawal of said master key tumblers from said circular grooves and a movement of said barrel longitudinally within said casing until said pass key tumblers are alined with said circular 90 grooves. 95
12. In a master key cylinder lock, a barrel, two sets of interposed tumblers carried thereby and normally protruding therefrom, one adapted to be operated by a master key and the other by an individual or pass key, the operation of either set permitting the tumbler-carrying barrel to be rotated to actuate the locking mechanism. 105
13. In a master key cylinder lock, a casing, a barrel rotatably mounted in said casing, means associated with said barrel and normally coacting with said casing to prevent rotation of said barrel, a part of said means being adapted to be operated by a master key and another part by an individual or pass key, the operation of either of said parts permitting rotation of said barrel. 110
14. The combination in a cylinder lock having the usual rotatable barrel, of an inclosing casing therefor provided with a longitudinal groove and a circular groove, and a plurality of independently operable tumblers carried by said barrel, one engaging the longitudinal groove of said casing and another engaging the circular groove thereof. 120
- In testimony whereof, I have subscribed my name.

DILLWYN M. BELL.
